UNITED STATES PATENT OFFICE.

WILLIAM RICHARD WHITE, OF BLOOMINGTON, ILLINOIS.

DESIGN FOR A LATCH-LEVER.

SPECIFICATION forming part of Design No. 31,974, dated December 12, 1899.

Application filed October 2, 1899. Serial No. 732,415. Term of patent 14 years.

To all whom it may concern:

Be it known that I, WILLIAM RICHARD WHITE, a citizen of the United States, residing at Bloomington, McLean county, State of Illinois, have invented and produced a new and original Design for a Latch-Lever, of which the following is a specification.

The accompanying drawing shows in side elevation a latch-lever embodying my design. The leading feature of my design consists of an arm 1, one end of which has a cross-head 2 in the form of a twist, and the other end has a laterally-bent portion 3 in the form of a crank. One end of the cross-head has 15 an opening 4 and the other end has a bent portion 5. The arm, the cross-head, and the

crank portion all lie in substantially the same plane. The bent portion 5 of the cross-head lies substantially parallel with the main portion 1 and is nearer thereto than the end 6 20 of the crank.

Having described my invention, I claim—
The design for a latch-lever substantially as herein shown and described.

In testimony whereof I have signed my 25 name to this specification in the presence of two subscribing witnesses.

WILLIAM RICHARD WHITE.
